CLAIM

The ornamental design for a bra, as shown and described.

DESCRIPTION

FIG. 1 is a front perspective view of a bra showing our new design;

FIG. 2 is a front view thereof; and,

FIG. 3 is an opposite side front perspective view thereof. The broken lines immediately adjacent to the shaded area define the bounds of the claimed design and form no part thereof. The broken lines depicting the remainder of the bra form no part of the claimed design.
